CLAIM

The ornamental design for a dose cup for liquid medicinal formulations, as shown and described.

DESCRIPTION

FIG. 1 is a perspective view of a dose cup for liquid medicinal formulations;

FIG. 2 is front view thereof;

FIG. 3 is a right side view thereof;

FIG. 4 is a rear view thereof;

FIG. 5 is a left side view thereof;

FIG. 6 is a top view thereof; and,

FIG. 7 is a bottom view thereof.

The broken lines are shown for the purpose of illustrating parts of the article as well as boundaries of the claim. None of the broken lines form part of the claimed design.

1 Claim, 3 Drawing Sheets
